PILOT LIGHT

Clarence H. Kehm, Chicago, Ill.

Application October 10, 1938, Serial No. 234,157

3 Claims. (Cl. 200—167)

This invention relates in general to a pilot light shunting a circuit which is opened and closed for turning on an electrical load, and is more particularly described in connection with an electrical switch in which the pilot light would be illuminated when the switch is open and will be extinguished when the switch is closed.

One of the principal objects of this invention is in the provision of a pilot light switch in which the light will be automatically illuminated when the switch is turned off so that the latter may be more readily found in the dark.

An important object of the invention is in the provision of a pilot light of the gas filled or neon type which has very high or substantially infinite resistance when cold, and which has a definite potential flash point and a very low current consumption when it is lighted.

A further object of the invention is in the provision of a pilot lamp which is incorporated as a part of an ordinary switch without changing any existing wiring installation but simply providing a lamp opening in the switch plate and inserting a lamp in the switch box below the plate connected in shunt with the switch to the circuit controlled by the switch.

Other and further objects of the invention will appear hereinafter, the preferred construction and embodiment being illustrated in the accompanying drawing, in which

Fig. 1 is a diagrammatic view of a circuit controlled by a switch with this pilot light connected in shunt across the terminals of the switch;

Fig. 2 is a side elevation of a switch with parts broken away for clearness and a panel plate therefor;

Fig. 3 is a face view of a switch block of this type with the face plate removed; and

Fig. 4 is a view of a pilot lamp of the type contemplated, showing the filament terminals in section.

It is frequently desirable to provide a visible indication of whether a switch is open or closed; the simplest form for the application of a switch pilot light may be for the purpose of indicating the location of the switch itself in the dark. Another obvious use for an installation of this kind is in the provision of a pilot lamp in connection with a switch for controlling a load at a distance, the lighting of the pilot lamp indicating that the load is not connected, as well as the position of the switch. A pilot lamp of this kind is highly desirable in any location normally in the dark where it is desirable to indicate the location of the switch, as for con-

trolling a larger illuminating light or installation.

This invention is particularly described in connection with an electric lamp as indicated in Fig. 4, of the gas filled or neon type, having filaments 6 and 7 with corresponding terminals 8 and 9 which are spaced apart, the filaments being connected to a screw shell 10 and end contact 11 respectively, and the terminals being spaced apart so that when cold the lamp has a very high, if not an infinite, resistance but has a definite flash point at which an applied voltage will cause a current pass between the terminals so that they will glow brightly. The present invention is not intended to cover specifically a lamp of this type as it is commercially available for various flash voltages, it has a very low current consumption, and being of the filamentless type, it has long life and service.

As shown in Fig. 1, a lamp 12 of this type is connected by conductors 13 and 14 to the terminals 15 and 16 of a switch 17 which controls an electrical load indicated as 18 which has a conductor 19 connecting it to a positive source of electrical supply, and has a conductor 20 connecting the other side of the load to one terminal 16 of the switch, the other terminal 15 of the switch being connected by a conductor 21 to the other or negative supply main.

When the switch is open as shown in Fig. 1, the lamp 12 is connected by its conductors 13 and 14 in series with the load through its conductors 19, 20 and 21. This will cause the lamp 12 to glow brightly, indicating that the switch 17 is open. When the switch is closed the terminals of the lamp 12 are short-circuited, no current flows through the lamp, and the load 18 receives its normal operating current in the proper manner. The resistance of the lamp 12 is so high that no appreciable current flows through the load 18 and the wattage required by this lamp is so small as to be practically negligible even if the lamp is kept illuminated practically continuously.

In an actual installation of the pilot lamp, it is incorporated in connection with or as a part of a switch block 25, usually formed of porcelain or other insulating material, having screw terminals 15' and 16' for conductors 21 and 20 joined by it and having a supporting metal strap 26 secured to the block 25 with eyelets 27 at the ends by means of which it secures the block in an electric conduit box (not shown) and having threaded perforations 28 to which an apertured face plate 29 is secured by screws 30. Pivotally mounted in the strap 26 and extending through an

opening in the face plate is a switch tumbler 31 which is moved oppositely in a well known manner to turn the switch off or on.

Adjacent to the block, at the end or one side 5 thereof, and formed integral therewith, is a socket 32 for receiving the lamp 12 which is seated therein below the surface of the plate 29 and in the plate is a recess or aperture 33 opposite the lamp or through which the illumination 10 of the lamp may be observed.

This socket provides for the attachment of a conductor 34 extending from the end terminal 11 of the lamp to one of the terminal screws 15' of the insulating block and a fastening clip 35 extends to the interior of the socket for providing a connection with the threaded shell 10 of the lamp which is connected by a conductor 36 with the other screw terminal 16' of the switch plug.

Thus it is seen that a new switch plug having 20 the additional socket 32 may simply be substituted for the ordinary switch plug of the present control switch and a new apertured face plate, as 25 29, may be substituted for the ordinary type of face plate without such perforation as now commonly employed, without materially changing the lighting equipment or installation. With this construction it is apparent that the switch and pilot light is an integral unit. When the switch which it shunts is opened the terminals of the 30 pilot lamp will have nearly the same impressed voltage as the electrical energy of the source, irrespective of the resistance of the load, the load and switch 12 then being in series which will cause the pilot light to glow brightly. As soon as 35 the switch is closed the terminals of the pilot light will be short-circuited and the light will be extinguished.

It is obvious that this pilot lamp may be used in a great variety of installations where it is 40 desirable to indicate whether a circuit controlling a load is in operative connection or not.

I claim:

1. As a unitary self-contained structure, a switch for controlling an electric circuit, said 45 switch embodying an insulating supporting block, circuit terminals supported by the block, a switch mounted upon said block and included in the circuit with said terminals, a lamp socket integral

with said block, a shunt circuit around said switch and in which shunt circuit said socket and said terminals are included, a lamp in said socket, said switch being operable to make and break connection between said terminals, said shunt 5 circuit being rendered active when the first said circuit is interrupted by the switch, and rendered inactive when the first said circuit is closed by the switch, in combination with a wall plate having an opening through which the switch projects and also a second opening through which 10 said lamp is visible.

2. As a unitary self-contained structure, a switch for controlling an electric circuit, said switch embodying an insulating supporting block, 15 circuit terminals supported by the block, a switch element mounted upon said block and included in the circuit with said terminals, a lamp socket integral with said block, a shunt circuit around said switch element and in which shunt circuit 20 said socket and said terminals are included, a lamp in said socket, said switch element being operable to make and break connection between said terminals, said shunt circuit being rendered active when the first said circuit is interrupted by 25 the switch element, and rendered inactive when the first said circuit is closed by the switch element, in combination with a wall plate having an opening through which a switch operating handle projects and also a second opening 30 through which said lamp is visible, all of said parts being disposed within the confines of the peripheral edge of said wall plate.

3. As a unitary self-contained article of manufacture, an insulating supporting block, a switch device mounted upon said block, a lamp socket integral with said block, a pair of terminals for a service line controlled by said switch device, a shunt circuit for said socket around said switch, said terminals being common to said service line 40 and said shunt circuit, said switch being operable to cause said service line and said shunt circuit to be rendered active and inactive in opposition to each other, and means whereby a wall or face plate may be detachably secured to said supporting block.

CLARENCE H. KEHM.
